United States Patent Office

Des. 195,413
Patented June 11, 1963

195,413

SHOE RACK

David C. Crawford, Cincinnati, Ohio, assignor to Ekco Products Company, Chicago, Ill., a corporation of Delaware

Filed Sept. 7, 1962, Ser. No. 71,601

Term of patent 14 years

(Cl. D33—3)

Fig. 1

Fig. 3FIG. 1 is a top perspective view of a shoe rack, showing my new design.

FIG. 2 is a front elevational view thereof.

FIG. 3 is an end elevational view thereof.

I claim:

The ornamental design for a shoe rack, as shown.
